United States Patent Office

Des. 194,105
Patented Nov. 20, 1962

194,105

CUBE-TAP

John D. More, 5105 Rindle Road, La Sierra, Calif.

Filed Apr. 24, 1961, Ser. No. 64,867

Term of patent 14 years

(Cl. D26—1)

FIG. 1.

FIG. 2.

FIG. 3.

FIG. 4.

FIG. 5.

FIG. 7.

FIG. 6.

FIG. 1 is a front perspective view of a cube tap, showing my new design;

FIG. 2 is a rear perspective view thereof;

FIG. 3 is a front elevational view;

FIG. 4 is a rear elevational view;

FIG. 5 is a top plan view thereof;

FIG. 6 is a bottom plan view thereof; and

FIG. 7 is a side elevational view, the opposite side having the same appearance.

I claim:

The ornamental design for a cube tap, substantially as shown and described.
